UNITED STATES PATENT OFFICE.

IRA ABBOTT, OF WYANDOTTE, MICHIGAN.

ROTARY ENGINE.

No. 829,499.

Specification of Letters Patent.

Patented Aug. 28, 1906.

Application filed February 6, 1905. Serial No. 244,268.

To all whom it may concern:

Be it known that I, IRA ABBOTT, a citizen of the United States of America, residing at Wyandotte, in the county of Wayne and State of Michigan, have invented certain new and useful Improvements in Rotary Engines, of which the following is a specification, reference being had therein to the accompanying drawings.

This invention relates to improvements in compound rotary engines in which live steam or a similar motive agent is admitted into the first cylinder and used expansively in the several succeeding cylinders; and an object of the invention is to provide a construction employing a series of cylinders of equal size, with steam-passages so arranged that the steam from the first cylinder is divided among two or more of the next succeeding cylinders and is again divided as it passes from these cylinders among several of the next succeeding ones to provide for the proper amount of expansion without the necessity of greatly increasing the size of the succeeding cylinders over that of the first.

It is also an object of the invention to so construct the casing forming the cylinders as to greatly facilitate and cheapen the manufacture of the engine and to provide suitable means for simultaneously shifting the reversing-valves to reverse the engine.

A further object is to provide a construction which is very compact and efficient and has the several advantages of the particular construction, arrangement, and combination of parts, all as hereinafter more fully described, reference being had to the accompanying drawings, in which—

Figure 1 is a longitudinal vertical section of a device embodying the invention with three of the cylinders removed, one in vertical section and two in side elevation. Fig. 2 is a plan view of the lower half of the casing forming the cylinders and showing the end heads in section; Fig. 3, a transverse vertical section of the device on the line $x-x$ of Fig. 1 and showing the piston in elevation; Fig. 4, a similar section on the line $y-y$ of Fig. 1; Fig. 5, a detail perspective view of the lower part of one of the internal cylinder-heads, and Fig. 6 a similar view of the upper part of the same.

As shown in the drawings, 1 is a suitable cast base upon which is supported a casing

or body made in halves, the lower half 2 being bolted to the base, or it may be cast integral therewith, and the upper half 3 flanged and bolted to the lower half to form the cylindrical body or casing, which is bored out to form a series of cylinders 4 of equal size and provided with grooves 5 between the internal faces of the cylinders to receive a series of internal ring-shaped heads 6 for separating the cylinders, outer heads 7 being bolted to the ends of the body to close the same and provided with stuffing-boxes 8, through which the shaft 9 extends, said shaft being supported at its ends outside said boxes in suitable bearings 10.

Rigidly secured upon said shaft 9 and extending the full length of the casing is a hub 11, having formed integral therewith a series of rotary pistons 12, one for each cylinder 4 and of considerably less diameter than said cylinders, said shaft and pistons being supported eccentrically within the cylinders or casing, with the lower sides of said pistons in contact with the bottoms of the cylinders to serve as abutments for preventing the steam from passing around the pistons and to form a steam-space above each piston within the cylinders. In each piston are two oppositely-extending radial slots 13 to receive the radially-movable blades 14, the outer end of each of which is constantly held in contact with the face of its cylinder by providing each with a stud or roller 15 at each end to engage openings in guide-blocks 16, movable in grooves 17 in the ring-shaped heads 6 and in the outer heads 7, said grooves being arranged concentric with the cylinders.

The pistons are preferably cast integral with a continuous hub to facilitate the manufacture of the device, it being possible when so constructed to secure them to the shaft and then turn all up at once, thus insuring accuracy of alignment and uniformity of size and spacing, and to permit the ready assembling of the device when so constructed the internal heads 6 are made in the form of removable rings formed in two sections 18 and 19, (shown in Figs. 5 and 6,) the section 19 being just large enough to permit the hub portion 11 to pass into the center of the ring and said sections fit together to form a perfect ring and are held in alignment with each other by a tongue-and-groove connection 20. For the purpose of making these rings lighter

and cheaper they are cast hollow, as shown, and to prevent them from turning in their grooves 5 each is provided with a lug or pin 21 at the bottom of its section 18 to engage a hole in the casing.

An intake and an exhaust port 22 and 23, respectively, are formed in each cylinder 4 at each side thereof, and the inner face of the lower half 2 of the cylinder is grooved or cut 10 away in line with these ports to receive a slide-valve 24, which is of such a length that when moved longitudinally in its groove in one direction one end will cover the exhaust-port at that side of the cylinder, and the opposite end will be moved from over the exhaust-port at the opposite side, and openings 15 25 are also provided in each of said valves to coincide with the intake-ports, said openings being so arranged that when the valve is 20 moved to close the exhaust-port at one side of the cylinder the opening in that side of the valve will be moved into coincidence with its intake-port, and the opening at the opposite side will close its port. These valves thus 25 30 operate to reverse the engine by causing the steam to enter the opposite side of the cylinder, and to move said valves simultaneously each is formed on its lower side with a series of gear-teeth 26, engaged by a sector 27, secured on a rock-shaft 28, extending longitudinally within the base 1 and mounted in bearings therein, the casing being formed with openings 29, in which the sectors move.

The shaft 28 is rocked in its bearings to 35 move the sectors and shift the valves by securing a sector 30 upon one end thereof, which sector extends upward through a slot in the base between the supporting-standards of one of the bearings 10 and is engaged 40 by a worm 31 on a transverse shaft 32, mounted in bearings on said standards and provided with a hand-wheel 33 at each end, by means of which the shaft 32 is turned to actuate the worm and shift the sector. It is 45 evident that a lever might be substituted for the sector or that the means for shifting said sector might be differently arranged.

It is proposed in this engine to use the steam expansively, the steam being admitted 50 at boiler-pressure to the first cylinder and exhausted from this cylinder into the two next succeeding cylinders and from these two cylinders into the next three, the engine being constructed with six cylinders; but it 55 may be made with a greater or lesser number, according to the use to which it is to be put and the power required. We prefer this construction, as the cylinders may then be made all of the same size, thus making the parts interchangeable and the blades of the most efficient size. Steam is admitted to the first 60 cylinder through an opening 34 at its top, which connects with a passage 35, extending entirely around the cylinder and communicating with both of the inlet-ports 22 in said

cylinder. From the exhaust-port at one side of the first cylinder, as shown in heavy dotted lines in Fig. 2, a passage *a* extends downward and branches into two equal parts *c d*, which lead around to the intake-ports at the 70 opposite sides of the second and third cylinders, and from each exhaust-port of the second cylinder a passage *e* leads downward and is divided into two branches *f g* of unequal capacity, branch *f* being of such a size that 75 two-thirds of the steam will be conducted around to the intake-port of the fourth cylinder and branch *g*, uniting with branch *h* of the passage *i*, leading from the exhaust of the third cylinder, will supply an equal amount 80 to the intake of the fifth cylinder, the branch *j* of said passage *i* conducting two-thirds of the steam from said passage around to the intake of the sixth cylinder.

The passages *k l*, and *m*, leading from the 85 exhaust-ports of the fourth, fifth, and sixth cylinders, respectively, unite in a suitable exhaust-passage *n*, opening outward through the end of the base. The passages leading from the exhaust-ports at one side of the cylinder are the same as those leading from the exhausts at the opposite side thereof, and therefore the steam may be sent either way 90 through the cylinders by shifting the reversing-valves.

Screwed into openings in the upper half 3 of the casing opposite each internal head 6 is an oil-cup 36, and a small tube 37, secured in each section 19 of said heads, conducts the oil from said cups downward to suitable passages leading to the grooves 17 in said heads to lubricate the same and prevent the blocks 16 from binding or wearing.

The bearings 10 for the engine-shaft are provided with the ordinary brasses 38, made 105 in halves, and the lower halves are made adjustable vertically to allow for wear and keep the shaft supported at exactly the same distance from the bottom of the casing by providing set-screws 39, extending through the 110 bearing and engaging the bottom of said brasses to raise the same.

The heads of the cylinders being all removable and the casing made in halves, said casing may be put into a lathe and the cylinders 115 faced up, and at the same time the grooves 5 for the internal heads and the grooves for the valves 24 may be formed, thus greatly facilitating its manufacture.

In assembling the engine the sections 18 120 of the internal heads are first set in place in their grooves, the external heads slipped upon the ends of the engine-shaft in contact with the end pistons, and the pistons then set into the casing with the internal heads between and the shaft resting in its bearings. The blades, with their guide-blocks, are then 125 slipped into place, the upper sections 19 of the internal heads placed in position, and the upper half of the casing then bolted down, 130

the bolting of said casing firmly clamping the internal heads and preventing any possibility of their getting out of place or turning.

It will be seen that with this construction a 5 very compact, powerful, and efficient compound rotary engine having all of the advantages of an engine of this type may be manufactured at a minimum cost.

Having thus fully described my invention, 10 what I claim is—

1. In a compound rotary engine, the combination of a casing divided longitudinally into two parts and provided with a series of grooves in its internal face forming a series of 15 cylinders between and provided with passages for connecting steam from one to another of said cylinders, removable internal heads set in the said grooves in the casing between the cylinders and clamped therein by 20 the securing together of the two parts of the casing, a shaft extending longitudinally through the casing and heads, and a series of rotary pistons on said shaft within the cylinders and provided with movable blades.

2. In a compound rotary engine, the combination of a casing made in halves and provided with a series of grooves in its internal face forming a series of cylinders between, a series of steam-passages connecting the cylinders, ring-shaped heads to engage the said grooves and provided with grooves formed concentric with the cylinders, external heads bolted to the ends of the casing and provided with grooves concentric with the cylinders, a 30 shaft supported eccentrically within the casing by bearings at each end of said casing and extending through the external heads and the axial openings in the ring-shaped heads, rotary pistons supported by said shaft with 35 their lower sides in contact with the lower sides of the cylinders and provided with radial slots, blades in said slots, and guide-blocks in the grooves in the heads to guide the blades.

3. In a compound rotary engine, the combination with a series of rotary pistons mounted on a common shaft and provided with blades; of a casing divided by internal heads into a series of cylinders to receive said 50 pistons each of which is provided with an intake-port at one side and an exhaust-port at the opposite side, said casing being formed with a passage for admitting steam to the intake-port of the first cylinder of the series, a 55 passage leading from the exhaust-port of said first cylinder and divided into two equal passages opening into the intake-ports of the second and third cylinders, and passages leading from the exhaust-ports of the second and 60 third cylinders into the intake-ports of three or more of the succeeding cylinders in the series.

4. In a compound rotary engine, the combination with a series of rotary pistons 65 mounted upon a common shaft and provided

with blades; of a casing divided by internal heads into a series of cylinders to receive said pistons which pistons contact the cylinders at their lower side only and each of which cylinders is provided with an intake and an exhaust port at each side of this point of contact, and said casing being formed with a passage extending around the first cylinder in the series and communicating with both of its intake-ports, a passage leading from each of the exhaust-ports of the first cylinder and divided into two equal passages, leading around to the intake-ports of the second and third cylinders on the opposite side of the casing, and passages leading from the exhaust-ports of the second and third cylinders at each side of the casing and each divided into two or more passages leading around to the intake-ports of the succeeding cylinders at the opposite side of the casing; valves for 70 controlling the admission of steam into the cylinders through said ports; and means for operating said valves simultaneously.

5. In a compound rotary engine, the combination with a series of rotary pistons 75 mounted upon a common shaft and provided with movable blades; of a casing divided by internal heads into a series of cylinders connected by steam-passages formed in the casing and within which cylinders the pistons 80 are supported by their shaft with their lower sides in contact with the surface of the cylinders and each of which cylinders is formed with an intake and an exhaust port at each side of said contact-point and provided with a groove in its inner face between said ports; slide-valves to fit within said grooves and movable longitudinally therein to open and close said ports; and means for moving said valves simultaneously.

6. In a compound rotary engine, the combination with a series of rotary pistons mounted upon a shaft and provided with movable blades; of a casing divided by internal heads into a series of cylinders for said 90 pistons connected by steam-passages formed in the casing and each of which cylinders is provided with an intake and an exhaust port at each side and formed with a groove in the 95 lower side of its internal face between said ports and the casing being formed with holes opening through its lower side into the said grooves; slide-valves to fit within the said grooves and provided with openings to register with the ports and with gear-teeth on 100 their lower sides opposite the said holes in the casing; a rock-shaft mounted in bearings and extending longitudinally of the casing opposite said holes, sectors secured on said rock-shaft and extending upward in the holes into 105 engagement with the teeth on the valves; and means for rocking said rock-shaft to shift said valves simultaneously.

7. In a compound rotary engine, the combination of a casing divided horizontally into 110

an upper and a lower part and forming a series of cylinders, the lower part being formed with intake and exhaust ports for each cylinder and with steam-passages connecting said ports; internal ring-shaped heads to separate the cylinders and each formed of a lower section and an upper detachable section; a shaft; rotary pistons secured on said shaft, and spaced thereon by their hub portions to fit within the cylinders with the said hub portions extending through the axial openings in the ring-shaped heads; and detachable heads on the ends of the casing.

8. In a compound rotary engine, the combination of a casing divided horizontally into an upper and a lower part open at each end and provided with a series of internal grooves forming a series of cylinders in the casing between said grooves, the lower part of the casing being formed with intake and exhaust ports for each cylinder and steam-passages connecting said ports; detachable rings forming internal heads for the cylinders engaging the said grooves and each consisting of an upper and a lower section connected by tongues and grooves; external heads bolted to the ends of the casing; a shaft supported in bearings at each end of the casing; a hub portion of a length equal to that of the casing secured on the shaft; rotary pistons formed integral with said hub portion and provided with radial slots; and movable blades in said slots.

9. In a compound rotary engine, the combination of a casing forming a series of cylinders provided with intake and exhaust ports and steam-passages connecting said ports, ring-shaped members within the casing forming heads between the cylinders and provided with grooves concentric with the cylinders, rotary pistons supported within the cylinders with one side of each in contact with the surface of the cylinder and each provided with radial slots, blades movable in said slots, studs on the ends of said blades, guide-blocks in the grooves in the heads provided with openings to receive the studs, tubes extending downward into the heads from their upper sides and communicating with the grooves in said heads at their inner ends, and

oil-cups screwed into openings in the casing and communicating with said tubes.

10. In a compound rotary engine, the combination of a base; a casing on the base divided horizontally into an upper and a lower part flanged and bolted together and provided with a series of internal grooves with spaces between forming the internal face of a series of cylinders, each of which cylinders is provided with an intake and an exhaust port at each side and a groove in its face connecting said ports, and the lower part of the casing being formed with steam-passages connecting the exhaust-ports of one cylinder with the intake-ports of two or more of the succeeding cylinders; a series of ring-shaped heads engaging the grooves between the faces of the cylinders and formed in two sections provided with guide-grooves in each side concentric with the cylinders; a pin on each ring-shaped head engaging a hole in the casing to prevent the head from turning; external heads provided with stuffing-boxes and bolted to the ends of the casing; bearings at the ends of the casing; a shaft mounted in said bearings and extending through the stuffing-boxes and the axial openings in the internal heads; a hub portion of a length equal to the length of the casing secured upon said shaft; a series of rotary pistons having radial slots formed integral with said hub portion; blades in said slots; guide-blocks for the blades in the grooves in the heads; valves movable longitudinally in the grooves in the faces of the cylinders and provided with openings to coincide with the ports and with gear-teeth on their lower sides; a rock-shaft mounted in bearings on the base; sectors secured on said rock-shaft in engagement with the teeth on the valves; a sector on the end of the said rock-shaft; a worm to engage and move said sector; and a hand-wheel to turn said worm.

In testimony whereof I affix my signature in presence of two witnesses.

IRA ABBOTT.
